US00D517811S

(12) **United States Design Patent** (10) **Patent No.:** **US D517,811 S**
Daubenspeck et al. (45) **Date of Patent:** **** Mar. 28, 2006**

(54) **MOTORIZED STAIN REMOVAL BRUSH FOR INANIMATE SURFACES**

(75) Inventors: **Bradley Wayne Daubenspeck**, West Chester, OH (US); **Susan Tyler Ede**, Cincinnati, OH (US); **Paul Amaat Raymond Gerard France**, West Chester, OH (US); **Linda Shumansky Girard**, Union, KY (US); **Debora Ellon Kaylor**, Hamilton, OH (US); **Neil Anthony Litten**, Egham (GB); **Matthew Burtonwood**, Huddersfield (GB); **Jamie Trafford Stone**, Glossop (GB)

(73) Assignee: **The Procter & Gamble Company**, Cincinnati, OH (US)

(**) Term: **14 Years**

(21) Appl. No.: **29/182,097**

(22) Filed: **May 21, 2003**

(51) LOC (8) Cl. **04-02**

(52) U.S. Cl. **D4/102; D4/127**

(58) **Field of Classification Search** **D4/100, D4/102, 114, 127, 101, 104, 111, 138; D28/7, 15/21.1, 22.1, 28, 29, 180, 186-188; 68/213, 68/220; 401/28, 137, 183, 184, 186, 268, 401/270, 279; 601/114**

See application file for complete search history.

(57) **CLAIM**

The ornamental design for a motorized stain removal brush for inanimate surfaces, as shown and described.

DESCRIPTION

FIG. 1 is a perspective view of a motorized stain removal brush for inanimate surfaces showing our new design.

FIG. 2 is a front view of the motorized stain removal brush of FIG. 1.

FIG. 3 is a side view of the motorized stain removal brush of FIG. 1.

FIG. 4 is a rear view of the motorized stain removal brush of FIG. 1.

FIG. 5 is a top view of the motorized stain removal brush of FIG. 1; and,

FIG. 6 is a bottom view of the motorized stain removal brush of FIG. 1.

The broken lines immediately adjacent the shaded areas represent the bounds of the claim and all of the other broken lines are for illustrative purposes only. None of the broken lines form part of the claimed design.

1 Claim, 3 Drawing Sheets
